UNITED STATES PATENT OFFICE

THOMAS A. HILL, OF MANHATTAN BEACH, NEW YORK, ASSIGNOR TO LION MATCH COMPANY, INC., OF NEW YORK, N. Y., A CORPORATION OF NEW YORK

AUTOMATIC PACKAGING MACHINE

Application filed August 8, 1924. Serial No. 730,829.

My invention relates to improvements in automatic packaging machines, and more particularly has reference to and is illustrated in the accompanying drawings in its application to a match-book making machine. In such machines heretofore it has been customary to use endless conveyors moved intermittently for receiving and holding the cover blanks and the matches thereon and for conveying the same while the blanks are folded over the matches and secured thereto. In some cases the matches which are formed in cards are provided with shoulders at the ends so as to centralize the matches within the cover, and in cases where these shoulders are not provided, the matches usually are not properly centralized and the machine does not produce a uniform looking book, with the result that the sulphur of the matches frequently projects laterally beyond the side of the cover where upon coming in contact with the sulphur of other matches, is liable to ignite and cause trouble. In the present machine the cards of matches are not necessarily provided with shoulders, but are centralized in the cover blanks and are retained in their central position until secured therein.

In the accompanying drawings, I have illustrated in Fig. 1 in perspective, parts being broken away, and parts being omitted, a suitable form of match-book making machine, embodying an application of my invention. Fig. 2 illustrates in perspective, upon an enlarged scale, parts being broken away, a portion of said machine where the cover blanks and match cards are cut and assembled. Fig. 3 illustrates in perspective on an enlarged scale, parts being broken away, the conveying, folding, stitching, and tumbling mechanism, and Fig. 4 is a perspective view on an enlarged scale showing a suitable form of pin feed for the match strips.

Referring now more particularly to Fig. 1, 15 to 17 inclusive indicate the legs or supports of the machine, and 18 the drive shaft thereof. Any suitable form of driving mechanism such as an electric motor and suitable transmission may be employed for driving the drive shaft 18, such suitable mecha-

nism being shown in the co-pending patent application of Greenbaum, et al., S. N. 660,781. The paper or card 23 from which the match book cover blanks are to be cut may be passed into the machine from the left end and may be provided in a suitable roll as customary in such machines. Likewise a roll of double wound match card or two rolls of such match card may be fed into the machine also from the left end, the same passing through the chute 24 to the cutters hereafter to be referred to. The feed of the paper is intermittent and may be such as shown in the said co-pending Greenbaum, et al. application referred to, but the feed of the match card, though intermittent, is slightly different as hereinafter stated.

As the strip of cover blank 23 is fed rightwardly into the machine between the guides 25, 25', of the chute 23' it passes beneath the bridge 26 secured at opposite ends to the block 27 as indicated at 28. This block is provided with a passage 29 large enough to admit the strip of blank 23 which passes entirely through the block 27 and on to brackets or shelves such as 30 between guides such as 31 where it is cut by the knife 32. The two strips of match card passing down through the chute 24 are also fed through the block 27. For feeding the match cards 33 a suitable lever 34 is pivoted at 35 and the lower end rides upon a cam upon the drive shaft 18 causing the forked upper end to move right and left looking at Fig. 1. 36 (see Fig. 4) indicates a suitable block adapted to engage the side guide 37 of the match chute 24 and slides freely thereon. This block has pivotally mounted thereon at 38, a pin member, the back of which projects upwardly and is provided with a laterally projecting pin bearing 40 to hold the upper block 41'. The forked lever 34 engages the pin 40 and in moving rightwardly depresses the pin 39 connected thereto into the match strips, thereby depressing the spring 41 and, as the pin feed moves rightwardly, the offset 41' passes beneath the projection 42 from the block 27 (see Fig. 4). This pin feed brings the strip of matches to the proper position for the knife 43 to sever the same, and before the

55

65

70

75

80

85

90

95

100

knife 43 descends, the presser-foot 44 descends squeezing the two thicknesses of match strip 33 upon the top of the bridge 26 securely holding the same while the end of the strip is cut away as indicated at 47. The presser-foot 44 then lifts slightly allowing the pin feed to push the cutoff strip rightwardly through the block 27 and upon the end of the cover blank resting between the guides 31 upon the shelves 30. The pin feed then recedes leftwardly slightly to bring the strips of matches 33 in position beneath the knife 43 to cut the next sections, which matches are held in that position by the presser-foot 44, the block 27 being cut away at 48 to allow clearance for the lateral projection 44' of the presser-foot 44 thereunder, from which it will be seen that the match strip is held at both sides of the knife 43.

49 indicates a plunger which passes through the base of the block 27, the upper surface being level with the bottom of the groove 29 serving as a continuation of the floor of the chute 23' for the strip of cover blank. A sufficient amount of the cover blank strip now having been passed on to the shelves 30, and cut off strips of matches such as 45' having been pushed thereon and centralized by the open frame 50, the cover blank is now ready to be cut, the plunger 49 having lifted against the top of the groove 29 to hold the same in position. Simultaneously with the movement of the plunger 49, the plunger 51 moves upwardly to support the cover blank beneath the matches 45' and simultaneously the presser-foot 52 moves downwardly to press the matches 45' upon the cover blank 23 beneath which is the plunger 51 and while thus held at both sides of the knife 32, the said knife descends completely severing the cover blank. Instantly the blank has been severed, the plungers 51 and 52 descend about a quarter of an inch, throwing the outer ends of the severed blank upwardly as indicated at 53 and then the presser-foot 52 rises while fingers such as 54 carry the partly folded cover blank 23 and matches 45' rightwardly into the next zone of the machine. While these are moving rightwardly, the presser-foot 52 being lifted, the cover blank strip 23 again feeds beneath the frame 50 and other cutoff strips of match cards are fed into the frame 50 upon the end of the cover blank strip and the same set of operations again takes place.

55 In the next zone the partly formed match-book passes over the plunger 55 and a slide 56 pivotally connected to the lever 57 moves inwardly, throwing the larger flap of the blank over the matches, the presser-foot 58 lifting to clear the end of the flap. Another slide 59 pivoted to the lever 60 then moves inwardly laying over the smaller flap or scratch end 53' of the match-book and the plunger 58 returns pressing the same lightly in position preliminary to the next feed of

the partly formed book. The levers 57 and 60 are pivoted at 61, and the lower ends are operated by cams by the drive shaft 18. From this point, the partly formed book is now moved rightwardly in the direction of the 70 stitcher 209 by fingers 62 and is again moved rightwardly beneath the center of the stitcher by fingers 63 where the usual form of wire stitching is passed through the lower end of the book and matches. From this point, the 75 fingers 64 move the stitched book to the end of the line of feed from whence it is delivered either out of the machine or to a suitable stacker mechanism, indicated at 65, by an ejector 66 which engages the formed book 80 during the next operation of the machine.

Referring now more particularly to Fig. 3 it will be observed that the fingers referred to are mounted upon a rod 67 and that similar fingers at the back of the machine are 85 mounted on a similar rod 68 so that the book in being fed through the machine is pushed rightwardly at each end of the left side simultaneously. It will also be noticed that said fingers have lateral projections such as 69 which pass beyond the edges of the cover blank and engage the sides of the match strips, so that the match strips are fed centrally of the cover blanks. Other fingers such as 70 are also mounted upon rods such as 71 and a similar set of rods being also provided at the opposite side of the machine and having similar fingers such as 72, said rods such as 71 being slidably mounted in said rods such as 68 as indicated by the grooves 68'. 100 These fingers it will also be observed have lateral projections such as 73 which project beyond the opposite edge of the cover blank the same as the projections 69 of fingers such as 54. The rods such as 71 are connected 105 across beneath the line of feed by a suitable bracket such as 74 which is provided with a lug 75 with a pin for hinging links such as 76, the opposite ends of said links being penetrated by the pin 77. Other links such as 78 110 are also pivotally mounted upon a pin in lugs 79 projecting from the plate 80 which connects the outer rods such as 67, 68, from which it will be seen that as the pin 77 rises and falls, the fingers such as 62, 73 will come 115 together and separate, and it is intended that when the fingers such as 62, 73 come together that they will rise between the books and then separate while feeding the books rightwardly through the machine, then come together 120 again so as to pass downwardly between the books without interference, move leftwardly about an inch and a half and rise while together, then separate to engage the next set of books and move rightwardly through the 125 machine, and so on constantly feeding the books as they are formed from left to right through the machine. This is provided for as follows: A pair of vertical members 81, 82 are connected across the bottom and ride 130

upon a cam upon a drive shaft 18 which imparts vertical movement thereto. In the lateral portions of these members are mounted triangular members such as 83 having rods such as 84 which are also connected at the bottom and ride upon a cam upon the drive shaft 18, said cam being very similar in shape to the cam upon which the members 81, 82 ride, except that the latter cam is adapted to lift the members 83 slightly higher than the members 81, 82. Upon the outer ends of the pin 77 suitable sleeves or tubes 84' are provided and adapted to ride in grooves such as 85 so that when the members 81, 82 have lifted the fingers to a level with the books, the additional slight rise of the pin 77 will throw the fingers apart, thereby centralizing the matches within the covers and keeping them thus while the same are being fed. 20 This is due to the flattening out of the links such as 76, 78 by the rise of the pin 77.

Intermediate the ends of the pin 77 is pivotally mounted a suitable link such as 86, said lever sweeping backwardly beneath the feed of the machine, the right end of the link 86 being pivotally mounted in the top end of the lever 88, and the lower end of the lever 88 being adapted to be engaged by the cam 89 to provide the necessary longitudinal feed motion. As guide and support for the books in passing through the machine, suitable channels such as 90, 91 are provided. The left ends of these channels are preferably half cut away at the top for the obvious reason that clearance must be provided for the upwardly extending free ends of the cover blanks such as 53, 53' until they are laid over. This laying over is done at the second zone after the blanks have dropped from the first position, and after that zone the channels are closed on three sides as shown. At the several points of the channels between where the books stand during the different periods of the feed, suitable light flat springs such as 92 are provided, and rectangular holes such as 93 are provided through the centers of the channels to allow an angular portion such as 94 to project through said holes into said channels as separators to keep the books properly separated and in position while the fingers pass downwardly and leftwardly to begin the next period of feed operation. In this way any slight shifting of the matches or books during the feed and due to vibration of the machine or other cause, is prevented.

At the extreme end of the line of feed the formed book is fed either out of the machine or to suitable stacker mechanism indicated generally by the reference character 65.

60 The cut off length of splint 45', as it appears when ready to be enclosed in the cover blank, is frequently termed the comb and is thus referred to in certain of the appended claims.

65 Of course it will be understood that va-

rious modifications may be made in the construction and arrangement of parts without departing from the spirit of the invention as claimed.

I claim:—

1. In a match-book making machine, means for supporting a superimposed cover blank and comb, means for centralizing said comb upon said blank, means for partly folding said blank around said comb, means for continuing the centralizing of said comb upon said blank while the same is completely folded and secured thereupon, and means for intermittently moving said blank and comb between the match-book forming operations, 70 said means for intermittently moving said blank and comb comprising reciprocating racks between which the same are engaged. 75

2. In a match-book making machine, means for supporting superimposed cover blanks 80 and combs, means for centralizing said combs upon said blanks, means for partly folding said blank around said combs, means for continuing the centralizing of said combs upon said blanks while the same are completely folded and secured thereupon, means for intermittently moving said blanks and combs between the match-book forming operations, 90 said means for intermittently moving said blanks and combs comprising reciprocating racks between which the same are engaged, 95 and guides through which said blanks and combs are moved by said racks.

3. In a match-book making machine, means for supporting superimposed cover blanks 100 and combs, means for centralizing said combs upon said blanks, means for partly folding said blanks around said combs, means for continuing the centralizing of said combs upon said blanks while the same are completely folded and secured thereupon, means for intermittently moving said blanks and combs between the match-book forming operations, 105 said means for intermittently moving said blanks and combs comprising reciprocating racks between which the same are engaged, guides through which said blanks and combs are moved by said racks, and separating members adjacent said guides for separating said associated blanks and combs as the same are 110 successively moved through said guides. 115

4. In a match-book making machine, means for supporting superimposed blanks and combs, means for centralizing said combs upon said blanks, means for partly folding said blanks around said combs, and means for continuing the centralizing of said combs upon said blanks while the same are completely folded and secured thereupon, means for intermittently moving said blanks and combs between the match-book forming operations, 120 said means for intermittently moving said blanks and combs comprising reciprocating racks between which the same are engaged, 125 means for moving said racks oppositely for 130

centralizing said combs in said blanks, and also for moving said racks together and rectilinearly for moving said associated blanks and combs through said machine.

5. In a match-book assembling machine, means for supporting superimposed covers and combs, centering means for centralizing said combs upon said covers, means for folding said covers over said combs and means for securing the same therein, said feeding means having a longitudinal substantially rectilinear motion.

6. In a match book making machine, means for supporting superimposed covers and combs, means for centralizing the combs on the covers, means for partly folding the covers around the combs, means for completing the folding of said covers, means for securing the covers to the combs, means for continuing the centralizing of the combs on the covers while the covers are completely folded and secured to the combs, and means for intermittently moving the covers and combs between the match book forming operations, said means for intermittently moving the covers and combs comprising reciprocating racks between which the covers and combs are periodically positioned.

7. In a match book making machine, means for supporting superimposed covers and combs, means for centralizing the combs on the covers, means for partly folding the covers around the combs, means for completing the folding of said covers, means for securing the covers to the combs, means for continuing the centralizing of the combs on the covers while the covers are completely folded and secured to the combs, means for intermittently moving the covers and combs between the match book forming operations, said means for intermittently moving the covers and combs comprising reciprocating racks between which the covers and combs are periodically positioned, guides through which the covers and combs are moved by said racks, and separating members adjacent the guides for separating the cover and comb assemblies as they are successively moved along the guides.

8. In a match book making machine, means for centralizing combs on covers, means for partly folding the covers around the combs, means for completing the folding of said covers, means for securing the covers to the combs, means for continuing the centralizing of the combs on the covers while the covers are completely folded and secured to the combs, means for intermittently moving the covers and combs between the match book forming operations, said means for intermittently moving the covers and combs comprising reciprocating racks, means for moving the racks oppositely to engage with opposite edges of the cover and comb assemblies to centralize the combs with respect to

the covers, and means for also moving the racks together rectilinearly to advance the cover and comb assemblies through the machine.

9. In a book match assembling machine, means for supporting a comb in superimposed relation to a cover, means for folding the cover to enclose the comb therein, and means for centralizing the comb with respect to the cover during the complete folding operation.

10. In a book match assembling machine, means for supporting a comb in superimposed relation to a cover, means for folding the blank to enclose the comb, means for permanently securing the comb within the thus completed cover, and means for centralizing the comb within the cover during the operations of folding the cover blank and securing the cover and comb together.

11. In a book match assembling machine, means for moving a cover blank with a superimposed comb along a predetermined path, with a cover in partially folded condition, means arranged along such path to complete the folding of the cover and to thereafter attach the cover to the comb enclosed therein, and means for centering the comb within the cover while the folding of the latter is completed and also during the operation of securing the comb within the completely folded cover.

12. In a book match assembling machine, means for supporting a comb and a cover, folding mechanism for thereafter partially folding the cover, additional folding mechanism for thereafter completing the folding of the cover, securing mechanism for thereafter securing the comb within the fully folded cover, and means for periodically centering the comb within the cover, said periods of centering operation being timed to occur while the cover is being folded and while the comb is being attached to the cover.

13. In a book match assembling machine, means for supporting a superimposed comb and cover, means for completely folding the cover to house the comb therein, means for thereafter securing the comb within the cover, and means for periodically centering the comb within the cover, said periods of centering operation being timed to occur during the folding of the cover and during the securing of the comb to the cover.

14. In a book match assembling machine, means for folding a cover about a superimposed comb, means for securing the comb within the cover, means for periodically moving the comb and cover successively into cooperation with said folding and securing means, and means for periodically centering the comb with respect to the cover.

15. In a book match assembling machine, means for partially folding a cover blank about a superimposed comb, a folding device spaced from said means, mechanism for

transporting the partially folded cover from said means to said folding device, and means for centralizing the comb within the cover after they have left the first folding means 5 and before the second folding operation is completed by the folding device.

16. In a book match assembling machine, means for periodically feeding a cover blank and a superimposed match comb along a predetermined path, devices arranged along said path for successively forming the comb and cover assembly into a completed book match, and means for periodically centralizing the comb within the cover blank as they are moved along such predetermined path.

17. In a book match making machine, means for partially folding a cover blank around a superimposed comb, means for completing the folding of the cover blank, 20 means for securing the comb within the completely folded blank, and means for centralizing the comb with respect to the blank, while the blank is completely folded and secured thereto.

18. In a book match making machine, means for partially folding a blank around a superimposed comb, means for completing the folding of the cover blank, means for securing the comb within the completely folded blank, and means for periodically centralizing the comb with respect to the blank, while the blank is completely folded and secured thereto.

19. In a book match assembling machine, means for periodically feeding a cover blank and a superimposed comb of less transverse width than the cover blank along a predetermined path, devices arranged along said path for successively forming the comb and associated cover blank into a completed book match, and means for centralizing the comb on the cover blank while it is fed through a plurality of assembling operations.

20. In a match assembling machine, a suitable table, devices arranged along the table for successively forming a comb and associated cover blank into a completed book match, and means for feeding a cover blank with a superimposed comb of less transverse width than the cover blank along the table into cooperation with the several forming devices in succession, said feeding means comprising reciprocating racks between which the covers and combs are periodically positioned and which racks are provided with hook shaped fingers adapted to engage the opposite edges of both the cover and comb to centralize the combs with respect to the covers.

21. In a match book making machine, a plurality of match book forming devices, and means for feeding a cover blank with a superimposed comb of less width than the cover blank to said devices in succession, said feeding means comprising a pair of racks, each

having thereon hook shaped fingers with the hook shaped fingers of the racks facing in opposite directions, means for moving said racks into position wherein the hook shaped fingers of the respective racks are positioned forwardly and rearwardly of the cover blank and comb, means for thereupon moving the racks oppositely with respect to one another to bring the hook shaped fingers into engagement with the front and rear edges of both the cover blank and comb to centralize the comb with respect to the cover blank and to thereupon move the racks rectilinearly in the same direction to simultaneously feed the comb and cover blank, the means for manipulating the racks being thereafter operable to return the racks to initial positions.

22. In a book match assembling machine, means for periodically feeding a cover blank and a superimposed comb of less transverse width than the cover blank along a predetermined path, said means embodying a reciprocating rack having thereon hook shaped fingers, a portion of each of which is adapted to engage with the edge of the cover blank and another portion of each of which is adapted to engage with the superimposed comb, whereby the comb and cover blank are each directly engaged by the hook shaped fingers which are so proportioned as to thereby centralize the comb with respect to the blank.

23. In a book match assembling machine, means for periodically feeding a cover blank and a superimposed comb of less transverse width than the cover blank along a predetermined path, said means embodying movable abutments engaging with the rear edge of the cover blank to push the blank along said path and also additional abutments movable with the first mentioned abutments and positioned to engage with the rear edge of the comb and extending sufficiently forward of the first mentioned abutments to centralize the comb with respect to the cover blank, both of said abutments being movable simultaneously in a direction of feed of the blank and comb to simultaneously feed such blank and comb along said predetermined path.

24. In a book match assembling machine, means for guiding a cover blank and a superimposed comb of less transverse width than the cover blank along a predetermined path, and means for simultaneously propelling both the blank and comb, comprising a reciprocating rack having thereon abutments to engage with and propel the cover blank and also abutments to engage with and propel the comb, said abutments being spaced apart in the direction of travel of the comb and blank a sufficient distance to thereby effect the centralizing of the comb on the blank.

25. In a book match assembling machine, means for guiding a cover blank and a

- superimposed comb of less transverse width than the cover blank along a predetermined path, and means for periodically moving the comb and cover blank along said path comprising a rack having thereon hooked shaped fingers, said fingers providing abutments to engage the cover blank and additional abutments to engage the comb with the latter abutments positioned sufficiently forward of the former abutments to effect the centralizing of the comb with respect to the blank, and means to operate the rack for the purpose of simultaneously feeding the combs and cover blanks in superimposed relation.
- 19 26. In a book match assembling machine, means for guiding a cover blank and a superimposed comb of less transverse width than the cover blank along a predetermined path, and means for periodically moving the comb and cover blank along said path comprising a rack having thereon hooked shaped fingers, said fingers providing abutments to engage the cover blank and additional abutments to engage the comb with the latter abutments positioned sufficiently forward of the former abutments to effect the centralizing of the comb with respect to the blank, and means for reciprocating the rack forwardly while the fingers are engaging with the cover
- 25 blanks and combs to impel said blanks and combs along said path for a predetermined extent and for thereupon reciprocating the rack rearwardly for substantially the same distance while the fingers are free from engagement with the cover blanks and combs to position the rack for a repetition of the operation stated.
- 30 27. In a match book making machine, means for supporting a superimposed cover blank and match comb, means for centralizing the comb on the blank, means for progressively folding the blank to enclose the comb, means for moving the blank and comb assembly through the successive blank folding operations, and means to continue the centralizing of the comb with respect to the cover blank during such successive folding operations.
- 35 28. In a match book making machine, means for supporting a superimposed cover blank and match comb, means for centralizing the comb on the blank, means for progressively folding the blank to enclose the comb, means for intermittently moving the blank and comb assembly through the successive blank folding operations, and means to continue the centralizing of the comb with respect to the cover blank during such successive folding operations.
- 40 29. In a match book making machine, means for supporting a superimposed cover blank and match comb, means for centralizing the comb on the blank, means for partially folding the blank, means for thereaf-
- 45 ter further folding the blank to enclose the

comb, means to continue the centralizing of the comb with respect to the blank during such latter folding of the blank, and means to secure the folded blank and comb together.

50 In testimony whereof I hereunto affix my signature.
